UNITED STATES PATENT OFFICE.

WILLIAM C. JENNINGS, OF NEW BRUNSWICK, NEW JERSEY.

GRATE.

SPECIFICATION forming part of Letters Patent No. 249,183, dated November 8, 1881.

Application filed June 14, 1881. (Model.)

To all whom it may concern:

Be it known that I, WILLIAM C. JENNINGS, of New Brunswick, in the county of Middlesex and State of New Jersey, have invented 5 certain new and useful Improvements in Grates; and I do hereby declare that the following is a full, clear, and exact description of the invention, which will enable others skilled in the art to which it appertains to make and use the 10 same, reference being had to the accompanying drawings, which form a part of this specification.

Figure 1 is a top view of my improved furnace grate and dumper. Fig. 2 is a longitudinal vertical sectional view of the same. Fig. 3 is a vertical cross-section through one of the shafts. Fig. 4 is a detail view of one of the segmental sections; and Fig. 5 is a side view of the device complete.

20 Corresponding parts in the several figures are denoted by like letters of reference.

This invention relates to shaking and dumping grates for stoves and furnaces; and it consists in certain improvements in the construction 25 of the same, which will be hereinafter fully described and particularly pointed out in the claims.

In the drawings hereto annexed, A A represent the sides of the stove or furnace, and B 30 B the detachable side rails, between which and the permanent sides boxes or bearings, C C, are formed for the ends of the rock-shafts D D, upon which the grate-sections are mounted, the said rock-shafts being square in cross-section, as shown, and provided with cylindrical 35 ends or journals mounted in the bearings above described. Each of the several rock-shafts is provided with a series of segmental, permanent or adjustable castings, E F, of different diameters, the large and small castings 40 being arranged alternate with each other, as shown. The said castings, when adjustable, are formed with square hubs projecting upon either side of the castings, as shown, so as to 45 properly space the several segments or castings of which each grate-bar is constructed.

The segmental castings E F consist individually of thin plates, which, in order to insure lightness and cheapness, are provided with 50 transverse openings or perforations G. The

said plates are also provided with broad rims or shoes H, the object of which is twofold, viz: first, to prevent the live coals from dropping down into the ash-box; second, to prevent the cinders from wedging between the grate-sections while shaking or dumping the grate. 55

The several rock-shafts or one of the castings mounted upon each in a longitudinal line are provided with downward-projecting arms or cranks I, connected by a longitudinal rod, J, the front end of which latter is connected by a toggle-joint, K, with a bell-crank lever, L, pivoted to a bracket, M, at the front end of the furnace. It will be seen that by operating said lever the said rock-shafts with their 60 intersecting segments are oscillated or vibrated, thus removing the ashes from the lower part of the fire-box or furnace to which the invention is applied. 65

From the foregoing description, taken in connection with the drawings hereto annexed, the operation and advantages of my invention will be readily understood. It is simple, convenient, durable, easily operated, and capable of being applied, with slight modifications, to 70 nearly all stoves and furnaces now in use. 75

Having thus described my invention, I claim and desire to secure by Letters Patent of the United States—

1. As an improvement in stoves or furnace-grates, the combination of a series of rock-shafts having segmental castings of different diameters arranged alternately thereon, substantially as and for the purpose set forth. 80

2. In a stove or furnace grate, the combination of a series of parallel rock-shafts having flanged segmental castings, as herein described, with the mechanism for operating the said rock-shafts simultaneously, consisting substantially of the horizontal connecting-rod K 85 and bell-crank lever L, pivoted in suitable brackets, M, as set forth. 90

In testimony that I claim the foregoing as my own I have hereto affixed my signature in presence of two witnesses.

WILLIAM CYROUS JENNINGS.

Witnesses:

MORRIS BAUER,
ANDREW AGNEW.
